UNITED STATES PATENT OFFICE

2,439,319

AIR PUMP ATTACHMENT FOR SEWING MACHINES

Walter O. Runcie, Lima, Peru

Application September 22, 1944, Serial No. 555,343

8 Claims. (Cl. 66—1.5)

1

This invention relates to an attachment for a sewing machine which will supply pulsating air pressure to a darning attachment and is an improvement over the construction embodied in the copending application filed by myself and Geza M. Keczeli, Serial Number 469,462, filed December 18, 1942, for Darning attachment for sewing machines, now Patent No. 2,390,329, issued February 4, 1947.

An object of this invention is to provide an attachment of this kind which can be secured to the supporting rod for the presser foot of a sewing machine and which may be coupled to the needle carrier so as to provide for pulsating air pressure.

Another object of this invention is to provide an attachment of this kind which is secured to the head of the sewing machine above the table thereof and which can be attached and removed without interfering with or requiring any change in the present parts of the machine, except for removal of the presser foot.

A further object of this invention is to provide an improved pulsating air generating means together with means for regulating the amount of air pressure generated or developed without varying the stroke of the plunger or piston.

A further object of this invention is to provide in a device of this kind an improved supporting means which permits lateral adjustment of the cylinder at the front of the head.

With the above objects and others which may hereinafter appear, the invention consists of the novel construction, combination and arrangement of parts as will be more specifically referred to and illustrated in the accompanying drawings wherein are shown embodiments, but it is to be understood that changes, variations and modifications may be resorted to which fall within the scope of the invention as claimed.

In the drawings:

Figure 1 is a detail rear elevation of a device constructed according to an embodiment of this invention mounted on the head of a sewing machine, the latter being fragmentarily shown.

Figure 2 is a view similar to Figure 1 from the front of the sewing machine with the plunger in its uppermost position.

Figure 3 is a sectional view taken on the line 3—3 of Figure 1.

Figure 4 is a longitudinal section partly in detail taken through the attachment removed from the sewing machine.

Figure 5 is a sectional view taken on the line 5—5 of Figure 1.

Figure 6 is a sectional view taken on the line 6—6 of Figure 4.

2

Figure 7 is a longitudinal section of a modified form of cylinder construction.

Referring to the drawings, the numeral 10 designates generally the head of a sewing machine which has a vertically reciprocating needle carrier 11 slidably mounted therein and a vertically adjustable foot carrying rod or shaft 12. A cylinder 14 is disposed on the end of the head 10 in a vertical position and includes a lower head 13 which is threaded onto the lower end of the cylinder 14. A nut 15 is threaded onto a stud 16 which is carried by the head 13, and a slotted disc 17 is interposed between the nut 15 and the adjacent face of the head 13. A supporting arm 18 is integral with and extends angularly from the slotted disc 17 and is provided at its lower end with a vertical U-shaped clamp 19. The clamp 19 is adapted to engage the lower end of the foot supporting member 12, and a clamping screw 20 which is threaded into the supporting member 12 tightly holds the U-shaped member 19 on the lower end of the foot carrying member 12.

The cylinder 14 has slidably mounted therein a plunger or piston 21 and the latter as here shown includes a cup-shaped flexible member 22 which is interposed between a pair of plates 23 and 24 mounted on the upper end of a piston rod 25. The retaining member 24 is preferably in the form of a nut which is threaded onto the upper reduced end 26 of the piston or plunger rod 25. The cylinder 14 adjacent the lower end thereof is provided with a vent opening 27 so as to provide for the inlet and outlet of air below the piston or plunger 21.

An upper head 28 is carried by the upper end of the cylinder 14 and an adjustable cap 29 overlies the upper end of the cylinder 14, there being a compression spring 30 between the head 28 and the inner side of the cap 29. A nipple 31 is threaded as at 32 into the head 28 and is formed above the head 28 with a laterally extending opening 33. The cap 29 includes a tapered nipple 34 having an opening 35 which may be moved into or out of registry with the opening 33 so as to regulate the amount of air which is to be released from the nipple 31 during the reciprocation of the plunger or piston 21.

The lower end of the piston or plunger rod 25 has secured thereto a right angularly disposed arm 36 which extends towards the needle carrier 11. The terminal end of the arm 36 has secured thereto an upwardly extending pin 37 which is inserted in the needle clamp 38 normally carried by the lower end of the needle carrier 11. In this manner as the needle carrier 11 is vertically reciprocated, the piston or plunger 21 will also

be reciprocated. The nipple 31 at its upper end is adapted to have engaged thereover one end of a flexible tube 39, the opposite end of the tube 39 being secured to a relooping needle apparatus, similar to that embodied in the copending application supra.

Referring now to Figure 7, there is disclosed a modified form of cylinder structure which includes a cylinder 14a having a head or cap 29a formed integrally with the upper end thereof and the nipple 31a in this instance is also formed integral with the cap 29a. It will be understood that the remaining structure including the plunger and supporting means hereinbefore described will be used with the cylinder 14a. As will be noted, the cylinder 14a is provided with a vent opening 21a adjacent the lower end thereof.

In the use and operation of this attachment, the adjustable cylinder 14 is secured in upright position by engaging the U-shaped clamp 19 with the lower end of the presser foot carrier 12. The pin 37 is then inserted in the place normally occupied by the needle and held in position by the needle clamp 38. As the needle carrier 11 is vertically reciprocated piston or plunger 21 will move therewith and the air above the piston or plunger 21 will pass through the nipple 31 and the hose 39, to the relooping needle assembly. The pressure generated by the reciprocating plunger or piston 21 may be regulated by adjusting exhaust opening 35 with respect to opening 33.

As hereinabove stated, this attachment may be mounted on the present parts of the sewing machine readily, it being only necessary to remove the presser foot from the supporting member 12, and the needle normally used in sewing is removed from the clamp 38 and the pin 37 inserted in this clamp so that plunger 21 will reciprocate with movement of the needle carrier. The provision of the slotted disc 17 permits lateral adjustment of cylinder 14 so that this attachment can be readily mounted on different types and makes of sewing machines.

What I claim is:

1. An air pump for attachment to a sewing machine which has a presser foot shaft and a reciprocating needle carrier, comprising a cylinder having an outlet at one end, a piston slideable in said cylinder, a supporting arm carried by the opposite end of said cylinder for attachment to a presser foot shaft to thereby support said cylinder solely from the presser foot shaft, and means connected to said piston and extending laterally therefrom for connecting said piston to a needle carrier whereby said piston will be reciprocated by said needle carrier.

2. An air pump as set forth in claim 1 including means regulating the air pressure generated by reciprocation of said piston.

3. An air pump as set forth in claim 1 wherein said latter connecting means includes an upwardly extending pin engageable in the needle holder of the needle carrier.

4. An air pump for attachment to a sewing machine which has a presser foot shaft and a reciprocating needle carrier, comprising a cylinder, a piston slideable in said cylinder, a piston rod secured to said piston and extending from an end of said cylinder, a supporting arm carried by said cylinder for attachment to a presser foot shaft to thereby support said cylinder from the presser foot shaft, a second arm fixed to and extending right angularly from said piston rod, and an upstanding pin carried by second arm

for removable attachment to a needle carrier and for operation therewith.

5. A pulsating air pump for attachment to a sewing machine which has a presser foot shaft and a reciprocating needle carrier, comprising an upright cylinder, a head on the lower end of said cylinder, a threaded stud carried by said head having a central bore, a supporting arm for said cylinder, a ring carried by one end of said arm formed with an elongated opening through which said stud loosely and adjustably engages, a nut threaded on said stud securing said ring and stud together, means releasably securing the other end of said arm to a presser foot shaft for supporting said cylinder solely from the presser foot shaft, a piston slideable in said cylinder, a piston rod secured to said piston and slideable through said stud, an angularly disposed arm secured to said piston rod, an upstanding pin carried by said latter arm for releasable engagement with a needle carrier for operation thereby, and means at the upper end of said cylinder for coupling the latter to a driven element.

6. An air pump as set forth in claim 5 wherein said latter named means includes an adjustable air release means whereby the air may be selectively discharged into the atmosphere.

7. An air pump for attachment to a sewing machine head having a needle carrier and a pressure foot shaft, comprising a cylinder, a piston reciprocating in said cylinder, means connecting said piston with the needle carrier of a head for operation thereby, and means supporting said cylinder laterally of a head, said supporting means including a supporting arm for attachment to the presser foot shaft, a ring carried by said arm formed with an elongated opening, a threaded stud carried by said cylinder engaging through said opening, and adjustable lengthwise thereof, and a clamping nut threaded onto said stud.

8. A pulsating air pump for attachment to a sewing machine which has a presser foot shaft and a reciprocating needle carrier, comprising an upright cylinder, a head on the lower end of said cylinder, a threaded stud carried by said head having a central bore, a supporting arm for said cylinder, a ring carried by one end of said arm formed with an elongated opening through which said stud loosely and adjustably engages, a nut threaded on said stud securing said ring and stud together, a piston slideable in said cylinder, a piston rod secured to said piston and slideable through said stud, an angularly disposed arm secured to said piston rod, an upstanding pin carried by said latter arm for releasable engagement with a needle carrier for operation thereby, means at the upper end of said cylinder for coupling the latter to a driven element, and means securing said arm on the machine in a position whereby said pin will be in alignment with the needle carrier.
